UNITED STATES PATENT OFFICE.

MELVIN BENT CUMBLER, OF HARRISBURG, PENNSYLVANIA.

AEROPLANE.

1,295,970.

Specification of Letters Patent.

Patented Mar. 4, 1919.

Application filed November 20, 1917. Serial No. 202,965.

To all whom it may concern:

Be it known that I, MELVIN BENT CUMBLER, a citizen of the United States, residing at Harrisburg, in the county of Dauphin and 5 State of Pennsylvania, have invented certain new and useful Improvements in Aeroplanes, of which the following is a specification, reference being had to the accompanying drawings.

10 This invention relates to aeroplanes and has for its object the provision of means for assisting in sustaining the aeroplane and preventing its too quick descent in case of anything going wrong with the engine.

15 A further object is to provide in connection with an aeroplane, an auxiliary plane shiftable into or out of operative position, and provide in connection with the auxiliary plane a gas bag or gas field, which becomes 20 distended and in operative position when the auxiliary plane is elevated to its operative position.

25 A further object of the invention is to provide in connection with the auxiliary plane and balloon or gas field, gas tanks containing gas under relatively high pressure and in which the gas is confined when the auxiliary plane and gas field are in in- 30 operative position, the gas being permitted to flow from these tanks into the balloon or gas field when the auxiliary plane is shifted to its operative position.

35 A further object is to provide means whereby guy wires connecting the auxiliary plane to the frame of the machine become effective when the auxiliary plane is elevated, and still another object is to provide improved means for latching the auxiliary plane in either its lowered or its elevated 40 position, this means being under the control of the aviator.

Other objects will appear in the course of the following description.

My invention is illustrated in the accompanying drawings, wherein:

Figure 1 is a front elevation of a biplane with the auxiliary plane and gas field in its raised and operative position, the fuselage of the machine at the forward end being 50 broken away;

Fig. 2 is a partial side elevation of an aeroplane of the biplane type with my improved auxiliary plane and gas bag connected thereto, the auxiliary plane being 55 depressed and the gas bag deflated;

Fig. 3 is a fragmentary side elevation of the aeroplane, as in Fig. 2, but with the auxiliary plane and gas field raised and inflated;

Fig. 4 is a fragmentary elevation partly 60 in section of one of the standards for supporting the auxiliary plane and raising it;

Fig. 5 is a diagrammatic horizontal cross section showing the manner in which the wires operating the latches are conducted to 65 the operating treadle;

Fig. 6 is an enlarged cross sectional view on the line 6—6 of Fig. 1;

Fig. 7 is a fragmentary vertical sectional view through the uppermost fixed plane and 75 one of the standards for supporting the auxiliary plane;

Fig. 8 is a vertical sectional view through the uppermost fixed plane and the auxiliary plane and gas bag showing the latter deflated and the auxiliary plane in lowered 75 position, the bracing struts for the fixed frame being in elevation; and

Fig. 9 is a fragmentary perspective view 80 of a portion of the fixed plane, the auxiliary plane, gas bag and hinged cover for the forward edge of the auxiliary plane.

Referring to these drawings, it will be seen that I have illustrated my improvement as applied to a flying machine of the 85 biplane type, though I do not wish to limit my invention to this application of it. In these figures, 10 designates the lower fixed plane of the flying machine and 11 the upper fixed plane. The machine is provided with 90 the usual fuselage including the vertical struts 12, the aviator's seat 13, and the controlling wheel 14. I do not believe it necessary to describe the construction of this machine, as it is of any ordinary or common 95 construction. Neither have I believed it necessary to illustrate the guiding rudders or the elevating or depressing rudders nor the means for warping the wing tips as these form no part of my present invention. 100

Normally resting upon the upper plane 11, and conforming approximately in shape thereto, is the auxiliary plane 15. This auxiliary plane is carried upon standards which are formed of two telescopic sections. Re- 105 movable sections are designated 16 and there are as many of these movable sections as may be desired. These sections 16 telescope within the tubular sections 17 which are attached to the fuselage or to the lower plane 110

10 in any suitable manner. Each movable section 16 is formed adjacent its lower end with a recess 18 adapted to be engaged by a spring actuated latch 19 mounted upon the 5 section 17, the latch operating through a perforation in the section. The section 16 is urged upward by means of a spring 20 within the section 17 when the latch 19 is released and when it moves upward the recess 18 will be engaged by a spring actuated latch 21 mounted upon the section 17 adjacent its upper end. It will thus be seen that normally the plane 15 will be held downward in proximity to the plane 11 15 against the action of the springs 20 but that upon a retraction of the latches 19, each standard 16 will be forced upward until the auxiliary plane 15 is elevated as illustrated in Figs. 1 and 3 and that the latches 21 will 20 hold the standard sections 16 in their elevated positions.

Attached to the underside of the plane 15 is a gas bag or gas field 22 which has a length approximately equal to the length of the plane 15 and so formed that when inflated the forward surface of the gas bag will extend upward and toward the forward edge of the plane 15. This gas bag is designed to be of any suitable capacity and is 25 normally deflated. For the purpose of inflating the gas bag, I provide one or more tanks, illustrated as two in number, and designated 23 which are carried upon the fuselage of the machine in any suitable 30 manner and extending upward from these tanks, through the plane 11, are the gas pipes 24.

Connecting the upper ends of these gas pipes 24 with the gas bag 22 are the flexible pipes 25 which have a larger diameter than the pipes 24. When the auxiliary plane 15 is disposed in contiguity with the plane 11 and the gas bag is deflated, the gas bag will be folded between the planes 15 and 11 in the manner illustrated in Fig. 8, the flexible pipe being also folded up in the space between the planes 11 and 15. When, however, the latches 19 are released, the valves 26 in the gas pipes 24 will be opened, allowing the 40 compressed gas within the tanks 23 to expand into the gas bag 22 as the auxiliary plane and gas bag move upward and thus the gas bag will be inflated and become operative as a supporting gas field. The 45 valves 26 may be of any suitable character and I have shown them as rotatable valves having arms 27 operatively connected by means of wires or cables 28 to a pedal 29 mounted upon fuselage in convenient relation to the driver's seat. Cables or wires 30 50 also connect the latches 19 to this pedal 29 so that when the pedal 29 is depressed by the operator, the valves 26 will be opened and the latches 19 released at the same time. I 55 do not wish to be limited to any particular

60 manner of guiding these cables or wires 28 and 30 from the various latches 19 and the valves 26 to the pedal but preferably they will pass over pulleys 31 as illustrated in Fig. 5. Any suitable direction changing 65 means may be used, however.

For the purpose of preventing wind pressure from entering in the space between the auxiliary plane 15 and the plane 11 when the plane 15 and the plane 11 are disposed in contiguity, as in Fig. 8, I provide a hinged cover 33, hinged as at 34 to the lower plane 11 and having the curved edge adapted to engage over the plane 15 to an extent sufficient to hold the cover closed by wind 70 pressure, but not sufficient to prevent the upward movement of the auxiliary plane under the action of the springs 20. Under this action, when the members 16 are released, the auxiliary plane 15 will move upward and automatically throw the cover 33 to an open position, as in Fig. 3. It is necessary to guy the auxiliary plane 15 and for this reason I provide the guy wires 35 which cross each other as illustrated in Fig. 85 3 and provide the forwardly and rearwardly extending guy wires 36. These guy wires are normally slack as illustrated in Fig. 2, but when the auxiliary plane 15 is raised under the action of the springs, these guy 90 wires will be rendered taut. It will be noted that the recess 18 is sufficiently longer than the latch 21 as to permit rings 20 to still urge the members 16 upward where they are latched in their projected positions, thus 95 placing a spring tension on the guy wires 25 and 36.

In Fig. 6 I illustrate means whereby the members 17 may be braced from the adjacent struts 12, this means comprising a 105 clamp 37 having sleeves embracing the strut and member 17 respectively, and this clamp being provided with eyes 38 for the attachment of guy wires.

The operation of this invention will be 110 obvious. Normally the auxiliary plane 15 is disposed as in Fig. 2, the gas bag 22 having previously folded up between the auxiliary plane and the plane 11 and the guy wires 36 and 35 being also folded up between these planes. In Fig. 2 these guy wires 36 are illustrated as being loose but this is purely illustrative as the guy wires will be relatively taut, but the slack portions thereof will be between the two planes. If now, 120 anything happens to the engine, so that it becomes necessary for the aviator to descend and it is desirable to provide auxiliary supporting power, the foot pedal 29 is depressed, which immediately releases the 125 rod 16 and opens the valves 26, the auxiliary plane is elevated carrying with it the gas bag, and the gas bag immediately becomes filled with gas, thus giving an additional support to the machine and permitting the 130

machine to descend relatively gradually to the ground, without the necessity of gliding downward for a long distance in order to make a landing.

- 5 In actual practice I have found that the auxiliary plane and the gas bag, when folded up as in Fig. 2, will not impede the forward movement of the aeroplane to any great extent and will not prevent or impede 10 the perfect operation of the aeroplane for the usual flying. The device adds greatly to the safety of the machine and in war would do away, to a considerable extent, of landing within the enemy's lines, as the aviator 15 could plane downward at a less inclination and thus a longer distance would have to be traveled in order to reach the ground than where a steep inclination was necessary in order to secure sufficient air pressure 20 as to sustain the machine in the air. Furthermore if, when banking, the angle of the machine became dangerous so that the machine would side slip, it would be only necessary for the aviator to release the auxiliary 25 plane and gas bag in order to secure a proper sustentation of the machine. Of course it will be obvious that the principle of my invention may be applied to various forms of aeroplanes and that various modifications might be made in the details of 30 construction without departing from the spirit of the invention.

Having described my invention, what I claim is:—

- 35 1. In a flying machine, a main fixed plane, an auxiliary plane movable toward or from the main fixed plane, means urging the auxiliary plane away from the fixed plane, means for supporting and guiding the auxiliary plane in its movement, means for holding the auxiliary plane in contiguity with the fixed plane, a normally deflated gas bag carried by the auxiliary plane, a gas tank containing gas under pressure, and 40 manually controlled means for releasing the auxiliary plane to permit it to shift to an operative position and for simultaneously opening communication between the gas tank and the gas bag.

- 45 50 2. A flying machine including a main fixed plane, an auxiliary plane disposed in contiguity and above the main fixed plane, a gas bag attached to the underside of the auxiliary frame and normally deflated, 55 tubular standards carried by the machine, supporting sections telescoping into said tubular standards and attached to the auxiliary plane, springs urging the sections and the auxiliary plane upward, latches 60 resisting the upward movement of the sections and the auxiliary plane, a gas tank having gas under pressure, a partly flexible conductor affording communication between the gas tank and the gas bag, a valve there-

in, and manually controlled means for 65 simultaneously opening the valve and releasing the shiftable sections of the standards and the auxiliary plane.

3. In a flying machine, a fuselage having an upper fixed plane, an auxiliary plane disposed above the upper fixed plane, a gas bag attached to the underside of the upper fixed plane, tubular standards mounted on the fuselage, standard sections attached to the auxiliary plane and extending down 70 into said tubular standards, springs urging the sections upward, latches resisting the upward movement of the sections and of the auxiliary plane, gas tanks mounted on the fuselage and having upwardly extending pipes extending through the upper fixed plane, flexible pipes connected to the fixed pipes and opening into the gas bag, valves on the fixed pipes, manually controlled means for simultaneously opening said 75 valves and disengaging said latches, and springs disposed in the tubular standards urging the shiftable sections upward when the latches are released.

4. In a flying machine, a fuselage having an upper fixed plane, an auxiliary plane disposed above the upper fixed plane, a gas bag attached to the underside of the auxiliary plane, tubular standards mounted on the fuselage, standard sections attached to the auxiliary plane and extending down 80 into said tubular standards, springs urging the sections upward, latches resisting the upward movement of the sections and of the auxiliary plane, gas tanks mounted on the fuselage and having upwardly extending pipes extending through the upper fixed plane, flexible pipes connected to the fixed pipes and opening into the gas bag, valves on the fixed pipes, manually controlled means for simultaneously opening said 85 valves and disengaging said latches, and springs disposed in the tubular standards urging the shiftable sections upward when the latches are released.

5. A flying machine including a fixed plane, an auxiliary plane disposed above the fixed plane, means for supporting the auxiliary plane and shifting it from a position of contiguity with the fixed plane to a raised position, a normally deflected gas bag mounted upon the auxiliary plane and normally disposed between the auxiliary plane and the fixed plane, a gas tank having valved communication with the gas bag, means for urging the auxiliary plane upward to a raised position, means for holding the auxiliary plane in a depressed position, and a cover 120 hinged to the forward edge of the fixed plane and extending over the forward edge of the auxiliary plane closing the space between

said planes when the auxiliary plane is disposed in contiguity to the fixed plane.

6. In a flying machine, a fuselage having an upper fixed plane, an auxiliary plane disposed above the upper fixed plane, a gas bag attached to the underside of the auxiliary plane, tubular standards mounted on the fuselage, standard sections attached to the auxiliary plane and extending down into said tubular standards, springs urging the sections upward, latches resisting the upward movement of the sections and of the auxiliary plane, gas tanks mounted on the fuselage and having upwardly extending pipes extending through the upper fixed plane, flexible pipes connected to the fixed pipes and opening into the gas bag, valves on the fixed pipes, manually controlled means for simultaneously opening said valves and disengaging said latches, springs disposed in the tubular standards urging the shiftable sections upward when the latches are released, crossed guy wires connecting the auxiliary plane to the fixed plane, and forwardly and rearwardly extending guy wires connecting the auxiliary plane to the fuselage, said guy wires being normally slack but being placed under tension when the auxiliary plane is raised.
7. A flying machine having an upwardly

bowed plane, a gas bag attached at its edges to the under face of the plane adjacent the margins of the plane and normally deflated, a second fixed plane disposed below the first named plane, means for normally holding the first named plane in contiguity to the second named plane with the deflated gas bag between the planes, and means for releasing the first named plane and urging it upward into spaced relation to the second named plane and for coincidentally inflating the gas bag.

8. In a flying machine, a fixed plane, an auxiliary plane movable toward or from the fixed plane, and a normally deflated gas bag disposed between the planes and attached to the surface of one of said planes and normally held in a folded position between and in contact with the planes, manually controlled means for relatively shifting the movable plane away from the fixed plane, and manually controlled means for inflating the gas bag.

In testimony whereof I hereunto affix my signature in the presence of two witnesses.
